UNITED STATES PATENT OFFICE

JOHN G. HOMAN, OF STEUBENVILLE, OHIO

TRUSS

Application filed July 10, 1928. Serial No. 291,574.

This invention relates generally to trusses or supports for hernia or rupture. It relates particularly to a truss including means for embodying the lever principle in order that greater pressure will be applied to the rupture than is applied to other parts of the abdomen when the abdomen expands.

My invention is adapted to securely hold the pad which supports the rupture in a wide variety of positions and to secure it in position even though the wearer assumes unusual positions of the body.

In the drawings which disclose the present preferred embodiment of the invention—

15 Figure 1 is a view showing the application of the truss to a single rupture;

Figure 2 shows the application of the truss to a double rupture;

20 Figure 3 is a perspective view of the pad for holding the rupture in place, and shows the means for regulating the pressure exerted against the rupture;

25 Figure 4 is a sectional view of the pad shown in Figure 3, and shows in dotted lines the position which the pad may assume in order to conform to the contour of the wearer;

30 Figure 5 is a perspective view of the adhesive pad employed in preventing the belt from slipping; and

Figure 6 is a perspective view of the adjustable buckle for maintaining the truss in position.

Referring to the preferred embodiment of 35 the invention shown in the drawings, the truss comprises a belt A which is of the usual construction. The belt is provided at its ends, as shown in Figure 6, with a buckle having fastening members 2 and 3 connected 40 to the opposite ends of the belt. The member 3 is provided with a pronged portion 4 so that the belt may be adjusted to the desired length. With the prongs inserted through the belt, the belt is put on and taken off from the body 45 of the wearer simply by unclasping the members 2 and 3. By the provision of a buckle of this character, after the belt has been once adjusted, it is a very easy matter to clasp and unclasp the members 2 and 4 in either 50 fastening or unfastening the truss.

The pad 5, which is adapted to retain the rupture in place, is provided with a facing 6 of soft pliable material which may conveniently be sponge rubber. The lower portion of the facing 6 is shaped to form a projecting portion 7, which is applied directly to the protrusion caused by the rupture. The backing of the member 5 is made up of a fabricated material 8 and in between the facing and the backing a flexible member 9 is arranged. This flexible member may be made of steel or any other desired material and is of such rigidity that it may be bent in order to conform to the body of the wearer. After being bent the member should retain the position which it has assumed. In Figure 4, the position of the pad is shown in dotted lines after the member 9 has been bent to conform to the body of the wearer.

A lever 10 which preferably is made of a resilient material such as spring steel, is pivotally connected adjacent the upper end of the member 9 by means of a snap-fastener 11. The snap-fastener 11 comprises an outer member 12, an inner member 13, a button 14, and a post 15 extending between the button and the upper member 12. The lever 10 is connected to the snap-fastener 11 by providing a hole in the lever and inserting the post 15 therein. The hole provided in the lever is made sufficiently large as to enable the lever to move up and down the post 15. The upper end of the lever is further provided with a slot 16 in which a screw 16' or other adjusting means is arranged so that by turning the screw the upper end of the lever is forced either toward or away from the pad. By turning the screw the lower end of the lever may be adjusted so that it assumes the dotted line position indicated at 17.

The lower end of the lever 10 is provided with a belt fastener 18 which is pivotally mounted at 18' to the lever. The belt holder should not pivot too freely on the lever and in order to prevent too free rotation the fastening means 18' is of such a construction that it requires some pressure to be exerted on the belt holder in order to turn it. If desired, a lock washer may be arranged be-

tween the lever and belt holder for this purpose.

In Figures 2 and 5, there is shown an adhesive pad 19 which is adapted to prevent the belt A from slipping. The adhesive pad is provided with a fabric covering 20 as is the usual custom, in order to protect the adhesive until the pad is to be used. The side of the pad opposite the protective covering 20 is provided with a male clamping element, not shown, which is adapted to cooperate with a female fastening element, not shown, arranged on the inner surface of a pad 21 which is fastened to the belt A.

As shown in Figure 2, the pad 21 is adjustably connected to the belt A by providing slits in the pad through which the belt extends. In order to prevent the belt from slipping, the protective coverings 20 are removed and the adhesive surface applied to the body of the wearer. The fastening elements are then snapped together thereby securely fastening the belt in the desired position.

The truss may be dis-assembled in order to clean it more easily by unsnapping the fastener 11 and unscrewing the screw 16.

From the above description it will be apparent that if the wearer of the truss assumes such a position, as in exercising, as to cause the diaphragm to expand, pressure will thereby be exerted on the upper end of the pad 5. With the belt fastened around the wearer's body, the pad 5 will pivot about the belt and belt fastener as a fulcrum. Since the belt holder is arranged on the lever 10 at a point nearer the lower end of the pad 5 than the upper end of the pad, a small amount of pressure exerted by the diaphragm on the upper end of the pad will exert a greater pressure on the lower end of the pad. This greater pressure is applied through the enlarged portion 7 directly to the rupture in order to maintain it in place.

In order to provide a means for adjusting the pressure of the pad against the rupture without materially increasing the pressure of the truss or pad against any other portion of the body, the lever 10 is pivotally mounted on the post 15. With this arrangement, if the screw is turned it varies the position of the belt holder so that either greater or less pressure is exerted by the pad against the rupture. The pressure of the pad against the rupture may therefore be materially increased without materially increasing the pressure of the pad on any other portion of the wearer's body.

It is to be understood that the form of the invention herewith shown and described is to be taken as a preferred example and that the invention may be otherwise embodied without departing from the spirit of the invention or the scope of the following claims.

I claim:

1. A truss comprising a pad adapted to

support a rupture, said pad having a rigid backing member, a resilient lever connected between its ends to said backing member, a waist band holder on the lower end of said lever, and a screw adjustment at the upper end of said lever for adjusting the pressure of the pad against the rupture. 70

2. A truss comprising a pad having an inwardly projecting portion at its lower end adapted to support a rupture, said pad having a rigid backing member, a resilient lever connected between its ends to said backing member, a waist band holder pivotally mounted at the lower end of said lever, and a screw adjustment at the upper end of said lever for adjusting the pressure of the pad against the rupture. 75

3. A truss comprising a relatively long narrow pad of soft flexible material having an inwardly projecting portion at its lower end adapted to support a rupture, a relatively long narrow backing member of material adapted to be bent to conform to the abdomen, a resilient lever detachably connected between its ends to the backing member and carrying at its lower end a pivotally mounted waist band holder, the upper end of said lever being slotted to receive an adjusting screw, and an adjusting screw extending through the slot into the backing member for adjusting the pressure of the pad against the rupture, the belt holder being below the center of the pad. 85

In testimony whereof I have hereunto set my hand. 90
